Patented Aug. 18, 1914.

UNITED STATES PATENT OFFICE.

CLEMENT T. SALVESEN, OF CHICAGO, ILLINOIS.

WINDOW.

1,107,450.

Specification of Letters Patent.

Patented Aug. 18, 1914.

Application filed December 8, 1913. Serial No. 805,445.

To all whom it may concern:

Be it known that I, CLEMENT T. SALVESEN, citizen of the United States, residing at Chicago, in the county of Cook and State 5 of Illinois, have invented certain new and useful Improvements in Windows, of which the following is a specification.

The subject-matter of the present invention is directed to new and useful improvements in windows, and aims particularly to provide a novel form of ventilator which may be manipulated to admit a small current of air into a room without necessitating the complete opening of the window sashes.

15 A further object is to provide ventilating devices of the character described, mounting these elements at the upper terminal of the upper sash and the lower terminal of the lower sash.

20 A yet further object is to removably mount the ventilating opening of the lower sash so that it may be quickly and conveniently applied to or removed from the lower sash as conditions may demand.

25 An object of equal importance with the foregoing is to mount the two sashes in such manner that they may be readily adjusted within the casing and held in adjusted position without employing for this purpose 30 weights and weight ropes.

This invention aims still further to provide a window embodying the features above set forth which may be cheaply manufactured, will be durable and efficient in its 35 action and, consequently, will not be liable to become broken or damaged in ordinary use.

The above and additional objects are accomplished by such means as are illustrated 40 in the accompanying drawings, described in the following specification, and then more particularly pointed out in the claims which are appended hereto and form a part of this application.

45 With reference to the drawings, wherein there has been illustrated the preferred embodiment of this invention as it is reduced to practice, and throughout the several views of which similar reference numerals designate 50 corresponding parts, Figure 1 is a perspective view showing the upper sash of the window slightly lowered; Fig. 2 is a section on the line 2—2 of Fig. 1; Fig. 3 is a section on the line 3—3 of Fig. 2; Fig. 4

is a section on the line 4—4 of Fig. 2; Fig. 55 5 is a perspective view illustrating in detail the ventilating plate which is carried by the lower sash of the window; and Fig. 6 is a perspective view showing the ventilating bars of the upper sash in open position extending at right angles to the sash. 60

Coming now to the detailed description of the drawings, and with particular reference to Fig. 1 in which the invention is best illustrated as an entirety, it will be observed 65 that this invention includes broadly a sash casing 10, and upper and lower sashes 11 and 12 respectively. The casing 10 is of the usual construction, being substantially rectangular in shape, and is provided on the inner face 70 of each side frame member with guide strips, as at 13 and 14 and 15 and 16. The rear edges of the side frame members of the window casing are provided with guide strips 75 17 and 18. It will thus be seen that the members 16 and 15 are disposed vertically in the casing and at approximate central points thereof. The middle portion of each of the members 15 and 16 is recessed, as at 19 and 20, in order to permit the positioning 80 of cog-wheels 21 and 22 which are rotatably mounted on pins or axles 23 and 24. These cog-wheels are arranged to mesh with the teeth of the rack bars 25, 26, 27 and 28 which are secured to the upper and lower 85 sashes, as will be readily observed upon reference to the figures.

From the foregoing description, it will be obvious that if the upper sash is moved upwardly through the casing, its rack bars 25 and 26 will rotate the cog wheels 23 and 24, and that these members will in turn impart a downward movement to the upper sash 12. It will also be noted that the downward movement of the lower sash will operate to move the upper sash upwardly through the casing by the same means. It now becomes apparent that by providing the rack bars and cooperating cog wheels, all necessity of employing window weights and 90 cords is eliminated, and that the sashes, being approximately equal in length, will balance one another in any adjusted position within the window casings. A suitable form of latch is, of course, provided as indicated 95 at 29 for locking the two sashes in closed 100 position.

As hereinbefore stated, one of the princi-

pal objects of this invention is to provide novel forms of ventilating devices which may be opened to permit a small current of air into the room without requiring that the window sashes be adjusted within the casings. In accomplishing this result, the present invention employs a pair of ventilating bars 30 and 31 which are approximately equal in length to one half the width 10 of the upper casing and are pivoted on the upper portion thereof by pivot pins 32 and 33. These ventilating bars are preferably pivoted at their adjacent terminals but, if so desired, the structure may be modified by 15 pivoting the ventilating bars at their upper terminals.

When it is desired to partially ventilate the room, it is only necessary to swing the ventilating bars on their pivot points by 20 grasping the handle bars 34 and 35, swinging the bars inwardly into the casing, and bring them at right angles to the plane of the sash.

In the preferred form, the guide members 25 14 and 16 are cut-away at their upper portions, as at 36 and 37, to produce a pair of stop shoulders 38 and 39. These stop shoulders are provided so that when desired the upper sash 12 may be moved downwardly a 30 slight distance through the casing and the ventilating bars swung inwardly, as in Fig. 3, to engage against the shoulders, thus holding the sash against further downward movement through the casing but, at the 35 same time, providing a ventilating space, as indicated at 40 in Fig. 2. It will thus be seen that even though the sashes remain securely locked, the ventilating bars 30 and 31 may be swung inwardly to provide two 40 ventilating openings, as indicated at 41 and 42, or that the upper sash may be moved downwardly a slight distance through the casing and the ventilating bars then moved into engagement with the shoulders 38 and 45 39, thus producing a ventilating opening of considerable size.

Coming now to the description of the ventilating device which is applied to the lower sash, and referring particularly to 50 Fig. 5, in which this feature of the invention is best illustrated, it will be observed that this element of the invention consists essentially in a substantially rectangular plate which is in length approximately equal 55 to the width of the sash. This ventilating plate, which will be hereinafter designated by the numeral 43, may be formed of sheet metal or, if so desired, from a relatively thin sheet of composition or wood. In order to 60 removably mount this plate on the lower sash, it has been formed adjacent each terminal with vertically extending slots, indicated at 44 and 45. Adjacent the lower terminal of each of these slots is formed an 65 offset notch as shown at 46 and 47. Screws

or other suitable fastening devices, indicated at 48, are applied to the lower portion of the sash 11, and are adapted to be inserted through the slots of the plate 43. In this connection, it is to be noted that the only 70 points through which the heads of these fastening devices will pass is at the juncture of the offset notches and the slots, and that consequently the plates will be held against displacement unless the heads of the fastening devices are brought into registration with the points at which the slots and notches merge into each other. 75

When the lower sash 11 is in closed position, as indicated in Fig. 1, the operator 80 moves the plate transversely through the sash by grasping the handle member 49, disposing the fastening devices in the notches, thus holding the plate against accidental displacement. When it is desired, however, to 85 move the upper sash downwardly such a distance as will permit the engagement of the ventilating bars 30 and 31 with the shoulders of the members 15 and 16 and, at the same time, to have the resultant opening between the bottom of the lower sash 11 and the window casing closed, it is only necessary to move the ventilating plate 43 transversely through the casing to bring the fastening devices into the slots so that the plate 90 may be dropped to bring its lower edge into engagement with the adjacent edge of the bottom frame member of the window casing. The space produced between the lower portion of the sash 11 and the window 100 casing by the upward movement of the sash may thus be closed so that only a small current of air will enter through the space between the upper portion of the casing and the ventilating bars 30 and 31. A suitable 105 hand grip, indicated at 49, may be provided for the lower sash in order to facilitate the operation of raising and lowering this member.

In concluding the description of the drawings, it is desirable to again direct attention to the fact that the window sashes and associated ventilating elements of this invention are constructed with all due regard to simplicity and efficiency, and that the window 115 may, consequently, be cheaply manufactured, will be durable and efficient in its action, and will not be liable to become broken or damaged in ordinary use. 110

In reduction to practice, it has been found 120 that the form of this invention illustrated in the drawings, and referred to in the above description as the preferred embodiment of the invention, is the most efficient and practical; yet realizing that the conditions concurrent with the adoption of this device will necessarily vary, it is desired to emphasize the fact that various minor changes in details of construction, proportion and arrangement of parts may be resorted to, when 125 130

required, without sacrificing any of the advantages of this invention, as defined in the appended claims.

What is claimed is:—

- 5 1. A window including a casing, vertical guides mounted therein, shoulders formed adjacent the upper terminals of the guides, a sash slidable in the casing, and a pair of ventilating bars pivotally mounted on the upper bar of the sash, the free terminals of the ventilating bars being engageable with the shoulders of the guide members whereby the sash may be lowered to provide a ventilating space between the upper sash bar and the upper end of the casing and may be held against further downward movement through the casing.
- 10 2. A window including a casing having vertical guide members provided adjacent their upper terminals with shoulders, a sash slidable in the casing, and a pair of swingingly mounted ventilating bars attached to the upper sash bar of the sash, said ventilating bars being movable to a position whereby the sash may be moved freely through the casing, being also movable to a position in which their free terminals engage the shoulders whereby the sash may be lowered to provide a ventilat-

ing space between the sash bars and the upper end of the casing and held against further downward movement through the casing.

- 15 3. A window including a casing having vertical guide members, a sash slidable between the guides, shoulders formed adjacent the upper terminals of certain of the guides, a pair of ventilating bars pivotally attached at their inner adjacent terminals to the approximate center of the upper sash bar of the sash, said ventilating bars being adapted to be longitudinally alined whereby they extend in the plane of the lower sash bar for permitting the sash to be freely moved through the casing, said sash bars being also adapted to be swung to engage their free terminals with said shoulders whereby the sash may be lowered to provide a ventilating space between the upper sash bar and the upper end of the casing, and then held against further downward movement through the casing.

In testimony whereof I affix my signature in presence of two witnesses.

CLEMENT T. SALVESEN. [L. S.]
